James Shelby Downard, deceased, late of Fort Thomas, Ky., by Naomi W. Downard, administratrix, Fort Thomas, Ky.

Application June 27, 1933, Serial No. 677,944

13 Claims. (Cl. 83—91)

This invention relates to a device for forming strings, fine particles, or sheets of asphalt.

It has been proposed to break up lumps of asphalt by applying heat thereto either in a container or upon a surface which has been heated thoroughly by gas burners or by combustion gases. Due to the fact that heat is transmitted very slowly through asphalt there is great danger of burning the asphalt before the same has been melted.

Electrical heating elements are well known in certain arts and these heating elements consist of spaced wires or coils of wires formed of resistance materials so that when a current is passed through the same the wires will become heated and such heat is then employed for various purposes.

It is an object of the present invention to provide a device in the form of a fabricated screen, or perforated plate made of resistance material which when a current is passed through the same will become heated for melting asphalt placed upon the screen which will pass through the restricted passages in the screen or perforated plate and form strings of asphalt which may be cut into small pieces by heated knives or broken up into small particles by streams of compressed air, water, or water containing fine mineral particles, the asphalt being employed is blown as a soft, sticky asphalt which may be mixed with finely divided mineral matter, or hard asphalt.

Another object of the invention is the provision of a screen or plate provided with a plurality of restricted passages upon which is adapted to be placed asphalt, the asphalt being melted when an electric current of proper strength is passed through the screen, thereby causing melting of the asphalt without danger of burning with the asphalt passing through the screen in the form of strings or sheets which may be cut up into proper lengths or broken up into fine particles to provide an element of a composition suitable for paving purposes.

This invention will be best understood from a consideration of the following detailed description, in view of the accompanying drawings forming a part of the specification; nevertheless, it is to be understood that the invention is not confined to the disclosure, being susceptible of such changes and modifications which shall define no material departure from the salient features of the invention as expressed in the appended claims.

In the drawings:

Figure 1 is a plan view of a device constructed in accordance with the principles of my invention,

Figure 2 is a transverse vertical section taken along the line 2—2 of Figure 1,

Figure 3 is a fragmentary view in perspective of one end of a screen,

Figure 4 is a plan view of a modified form of screen shown in Figures 1 to 3, inclusive,

Figure 5 is a transverse vertical section taken along the line 5—5 of Figure 4,

Figure 6 is a fragmentary end view of a portion of the screen shown in Figures 4 and 5,

Figure 7 shows more or less diagrammatically a circuit controlling the current to a screen,

Figure 8 is a side view in elevation of an oscillating container,

Figure 9 is a fragmentary vertical section of the device shown in Figure 8,

Figure 10 are fragmentary views in perspective of various forms of cutting devices employed in connection with the screens shown in Figures 8 and 9,

Figure 11 is a bottom plan view of the device shown in Figures 8 and 9,

Figure 12 is a fragmentary view in elevation of a modified form of the device shown in Figures 8 and 9,

Figure 13 is a bottom plan view of the device shown in Figure 12,

Figure 14 is a fragmentary vertical section taken along the line 14—14 of Figure 13,

Figure 15 is a vertical section of a further modified form of means for operating knives,

Figure 16 is a horizontal section taken along the line 16—16 of Figure 15,

Figure 17 is a fragmentary vertical section of another modified form of the device for breaking up asphalt,

Figure 18 is a plan view of a detail of the heating device employed in Figure 17,

Figure 19 is a vertical section of a modified form of the invention shown in Figure 17,

Figure 20 is a fragmentary vertical section of a still further modified form of the device shown in Fig. 17,

Figure 21 is a vertical section of a modified form of the device shown in Figure 20,

Figure 22 shows more or less diagrammatically a device for producing fine particles of asphalt,

Figure 23 is a bottom plan view of a portion of the device shown in Figure 22, and

Figure 24 is a fragmentary vertical section of an electrically heated knife employed in connection with the device shown in Figure 20.

Referring more particularly to the drawings, 10 8 designates a supporting frame formed of insulating material upon which is mounted a screen 11 16 constructed in accordance with the principles of my invention. The screen and frame may be of any size suitable for the purpose. While I have shown the screen as rectangular it may be square or circular. The insulating material must be porcelain, bakelite, or any other type which will not be injured by the heated screen.

The screen consists of a plurality of transverse 15 wires 12 formed of resistance material which are interwoven with longitudinally disposed wires 13 of the same material. The ends of the longitudinal wires 13 are clamped together by a pair of parallel electrical conducting strips 14 such as 20 copper and these strips are secured in place by means of lugs 15 carried by the framework 10 and nuts 16 threaded onto the lugs. It will be seen that the other ends of the wires 13 are connected with conducting strips as will be presently explained.

The lugs or posts 15 are connected with electric 25 wires 20 which extend to a common lead-in 21 which may be considered the positive side of an electric circuit. A resistance 22 is located within the circuit and may be of any type suitable for the purpose. A wire 23 leading from the resistance 22 may be connected with one terminal of the house current.

Wires 25 are connected to binding posts 26 carried by the supporting frame 10 and these posts are electrically connected with a pair of strips 27 which are similar in all respects to the strips 14. These strips are made of copper and form the outgoing terminals of that portion of the circuit which is included within the screen 11. A common wire 28 is connected with the wires 25 and extends to the other terminal of the house current and may be designated as the negative side, while the wire 21 represents the positive. Ends 40 of the wires 13 are clamped between the strips 27 by the binding posts 26 and the nuts on the said posts.

Proper current is supplied to the wire 21 which 50 passes through the copper strips 14, through the resistance wires 12 and 13. The current passing through these wires causes the same to be heated so that asphalt which is placed upon the wires will pass through the interstices and form strings of asphalt. An electrically heated knife or knives are located below the screen 11 for cutting off the strings into small pellets, as will be presently described.

In the modified form shown in Figs. 4 to 6, inclusive, it will be seen that instead of wires, metallic strips 30 formed of resistance material are longitudinally disposed on a framework 31 and rest upon a shoulder 32 formed at the upper periphery of the framework 31. This framework is 60 made of any suitable insulating material. All of the longitudinal strips are provided with spaced notches 33.

Transverse strips 34 likewise formed of resistance material are disposed in parallel relation 70 along the strips 30 and are likewise provided with notches which will be received by the notches 33 so that when the strips 34 are placed in position all of the tops of the strips will be in the same horizontal plane.

75 The adjacent ends of the strips 30 at one end of

the frame are secured to a copper strip 35 which has its ends connected with wires 36 and a lead-in wire 37 which is designated as the positive side of the circuit. A copper strip 38 has its ends connected to wires 39 which in turn are connected to 5 a common wire 40 also connected with the house current. Binding posts 41 and 42 are respectively employed at the opposite end of the screen connecting the strips 35 and 38 to the framework 31 and for clamping the ends of the wires 36 and 39 10 in position. The copper strip 38 is connected to the other ends of the strips or bars 30.

Asphalt of any type is placed upon the screen as illustrated in Figs. 4 to 6, inclusive, and the electric current is switched on. The strips 30 15 and 34 will become heated for melting the asphalt and causing the same to pass through the spaces and project beyond the screen in the form of strings of asphalt which may be cut by electrically heated knives as the asphalt projects beyond the screen. Streams of compressed air or 20 water, or a mixture of both water and air, or water containing fine mineral particles may be projected across the extruding asphalt to form fine particles of asphalt. 25

If it is desired to form sheets of asphalt instead of strings, the strips 34 may be readily removed from the strips 30 to provide elongated passages so that when the asphalt is placed on the heated strips 30 the asphalt will pass through the respective strips in the form of sheets and these sheets may be cut off in definite lengths.

Referring more particularly to Figs. 7 to 9, inclusive, it will be seen that a container 50 is mounted for rotation in opposite directions within 35 a housing 51. This rotation, however, is through a small arc as will be presently described.

A spur gear 52 is secured to a shaft 53 which extends inwardly of the housing 51 and a second gear 54 is secured to the inner end of the shaft 40 53 and meshes with a ring gear 55 secured to the container 50. A segmental gear 56 is pivotally mounted at 57 on the housing 51 and meshes with the spur gear 52. A connecting rod 58 is pivotally connected at 59 with the segmental 45 gear 56 and has an eccentric connection 60 with a gear 61 mounted on a shaft 62. The gear 61 is driven by a gear 63 which in turn is operated by an electric motor which is connected with a 50 source of current, not shown, and controlled by a switch in the usual manner.

A screen 65 is secured at 66 to the bottom of the container 50 but is insulated as shown at 67 from said container. A source of current is connected to the screen by means of wires 68 55 and 69.

The screen 65 is formed of some kind of resistance material such as nickel, chrome steel and may be constructed in accordance with any of the forms shown in Figs. 1 to 6, inclusive, or 60 the screen may be in the form of a metal plate provided with perforations 70.

A plurality of knives 71 are rigidly supported as shown at 72 by means of insulating material 73 which in turn is secured to a bracket 74 connected to the inner wall of the housing 51. These 65 knives or cutters are connected with a source of current through wires 75 and 76.

It will be noted that a housing portion 77 extends downwardly below the heated screen 65 70 and knives 71 in order to protect the screen and the knives from the loss of heat and also the asphalt passing through the screen.

The knives may be of any type such as a wire formed of resistance material, such as at 78 in 75

Fig. 10, or the knife or cutter may be in the form of a flat strip of metal, as shown at 71 or in the form of a bar or rod 79.

The current to the knives and to the screen are controlled by means of a switch 88 shown in Fig. 7, a transformer 81 and a thermostat 82. The capacity of the transformer, of course, depends upon the temperature required for heating the electric resistance screen or plate 65.

10 The operation of the device shown in Figs. 7 to 11, inclusive, is as follows: Asphalt or bitumen is placed within the container 50 either in a heated state or cold. The current is turned on in order to heat the screen or plate 65 and the 15 knives 71.

The motor 64 is started for oscillating the container 50 so that the heated screen 65 will be moved over the knives 71. As the asphalt is melted and passes through the perforations in 20 the screen or the plate the knives will cut the asphalt into small particles and these particles will then drop downwardly below the skirt 77 and may be collected in water or in a bath containing water and fine mineral dust as may be 25 desired.

In the construction shown in Figs. 12 to 14, inclusive, it will be found that a modified form of the cutting mechanism is employed. In this case the container 85 is held stationary and the 30 screen 86 is heated in the same manner as shown in Figs. 1 to 11, inclusive, and may be of the form of any one of the screens previously described.

The oscillating frame 87 formed of insulating 35 material carries vertically disposed knives 88 so that when the frame 87 is reciprocated these knives will be moved across the perforations in the screen 86 and cut off the protruding asphalt in such length as many be desired. It will be 40 appreciated that the smallness of the particles of the asphalt thus produced will depend upon the speed of the operation of the frame 87. An end of each of the knives 88 is secured to a strip of electrical conducting metal 89 and the other 45 ends of the knives are connected to a strip 90 formed of conducting material. This last-mentioned strip is connected to a wire 91 while the strip 89 is connected to a wire 92. These wires form a circuit and are controlled by the instrumentality disclosed in Fig. 7.

The frame 87 is mounted in guides 93 and is reciprocated by means of a rod 94 pivotally connected at 93 to the frame and eccentrically connected at 96 to a gear 97 which meshes with a 50 gear 98. The last-mentioned gear is driven by means of a motor 99 connected with a source of current (not shown).

The strips of conducting material 89 and 90 are secured to the frame 87 at one end by 55 means of a bolt 100 imbedded in the material of the frame 87. This frame is formed of non-conducting material and the projecting threaded end 101 of bolts 100 are employed as binding posts for the wires 91 and 92. The operation of 60 the device shown in Figs. 12 to 14, inclusive, is as follows: The container 85 is supplied with asphalt and the current to the screen 86 is switched on so that the screen will be heated. The current to the strips of materials 89 and 90 is also 65 switched on for heating the knives 88. The motor 99 is then operated and the frame is reciprocated carrying the knives 88 back and forth below the heated screen 86 so that when the asphalt protrudes from the screen 86 the knives 70 75 88 will cut off particles of lengths depending

upon the speed of movement of the frame 87. It will be noted that so far the knives are described as being heated and the purpose of this is to shear the asphalt in its heated condition while preventing chilling of the same.

In the modified form of the device shown in Figures 15 and 16 a container 105 carries an electrically heated screen 106 which is connected to a source of current by means of wires 107—108.

For the purpose of reciprocating the knives 109 carried by the endless chains 110 I have provided a gear 111 which is driven by a shaft 112, a gear 113 rigid with the shaft, a segmental gear 114 meshing with the gear 113, a rod 115 and a motor 116. The rod 115 is eccentrically connected at 117 with a disc 118 driven directly by the motor 116. The opposite end of the rod is pivotally connected at 119 to the segmental gear 114 which is pivotally mounted at 120 to a fixed part of the frame. Idling gears 121 co-operate 20 with the driving gears 111 for supporting the endless chain 110.

Collector members 122 are connected with chains 110 and wiper arms 123 connected with a source of current as indicated by the wires 14 25 supply the knives 109 with electric energy which is converted into heat due to the resistance of the metal of the knives. These knives are directly connected with the collector members 122 30 and these members are insulated from the endless chain 110.

As the motor is revolved and the current is switched to the knives 109 and the screen 106, the knives will be oscillated across the perforations 106* for cutting off the asphalt which passes through the perforations. The segmental gear 114 rocks the chains back and forth causing reciprocation of the knives.

A modified form of the heated screens is employed and instead of a woven wire screen 40 formed of resistance material or of a perforated plate formed of the same material, tubular members are formed of resistance material, as shown at 130, which extend downwardly through an insulating block 131. It will be noted that 45 the tubular members 130 are formed by bending a flat strip of resistance material into circular form but the two longitudinal edges of the material are spaced apart, as shown at 132, so that the insulating material 131 is exposed at 50 this portion. Strips of conducting metal 133 connect the various tubular members 130 together while conducting strips of metal 134 are connected to the strips 133. A source of current is passed through the strips 133—134 by means 55 of wires 135 and 136. A screen either in the form of a plate or fabricated material is located above the upper ends of the tubular members 130, as shown at 137, and are provided with perforations 138 which are adapted to align with the 60 tubular members 130. This plate or screen is connected with a source of current, as indicated by the wires 139 and 140 in order that it may be heated sufficient for aiding in melting the asphalt placed within the container 141.

It will be noted that the strips 131 are disposed in vertical planes and are imbedded in the insulating material 131. The insulating material in this construction and all of the constructions described in connection with this case is 70 formed of such material that it will be sufficiently resistant to heat in order that it may not be destroyed during the operation of the devices. The screen 137 is insulated from the container 141 as shown at 142.

The tubular members 130 extend slightly below the screen 137 in order to prevent short circuiting between the current passing through the tubular members and the screen 137.

- 5 Knives may be reciprocated across the lower edges of the tubular members 130 from which the melted asphalt extends or a current of compressed air or finely divided streams of water or water containing colloidal suspensions of mineral matter may be directed across the lower ends of these tubes for breaking the asphalt into fine particles.

- 10 In the modification shown in Fig. 19 it will be seen that the container 143 rests upon the block 144 formed of insulating material which is provided with passages 145 to receive tubular members 130^a which are identical in construction with the tubular members 130 shown in Figs. 17 and 18. The conductor metal strips 133^a are directly connected with the tubular members 130^a and these strips are connected with a source of current by means of the wires 146—147.

- 15 The upper end 147^x of the tubular members 130^a project above the upper face of the insulating block 144 so that when an electric current passes through the strips 133^a and the tubular members 130^a the asphalt will be melted and pass through said tubular members. Since current passes through the tubular members they 20 will be heated throughout the length thereof to maintain melted condition of the asphalt so that when heated knives are employed for cutting off the asphalt as it extends below the lower ends of the tubular members, as has been previously 25 explained, the knives will move towards the portions of the tubular members, as shown at 148, where the greatest amount of heat is in order to more efficiently cut off the particles of asphalt.

- 30 Instead of the knives, a stream of air may be directed against the lower ends of the tubular members 130^a for breaking the asphalt into small particles or fine streams of water containing fine mineral matter may be employed for the same purpose.

- 35 45 Referring more particularly to the modified form shown in Fig. 20 it will be seen that a plate 150 formed of resistance material is provided with passages 151. This plate is mounted upon a hollow box or casing 152 having a chamber 50 153 into which is directed hot gases from a pipe 154. The walls of the box or casing is formed of insulating material which will not be affected by the heat.

- 40 55 A ring 155 formed of insulating material rests upon the periphery of the plate 150 and a flange 156 of a container 157 rests upon the ring 155.

- 50 60 Metal tubes 157^a are passed through the chamber 153 and through passages 158 and 159 formed in the top and bottom of the casing 152. The upper ends of the pipes are aligned with the passages 151 in the plate 150.

- 65 70 Electrical resistance material formed of any suitable metal, as shown at 160, is carried by the lower end of the tubes 157^a. A wire 161 is connected with the resistance material 160 and with one terminal of a circuit. Intermediate wires 162 connect the resistance members 160 together while a wire 163 forms the other terminal of the circuit and is likewise connected with the resistance 65 75 160 at one end of the casing 153 so that when a current is passing through the wires 161 these resistances will be heated for heating one portion of the pipe for a purpose which will be presently explained.

A reciprocating frame 164 formed of insulating material carries knives 165 and the frame 164 may be reciprocated in any approved manner as has been disclosed in Figs. 8, 9, 12, 13, 15 and 16.

5 A knife 165 is shown more in detail in Fig. 24 and includes a casing 166 having a coil of electrical resistance wire 167 carried within the member 166 and this coil is connected with wires 168 and 169. As shown these wires are in turn 10 connected with a source of current for heating the resistance coils 167 for heating the knives so that they will properly shear the asphalt passing through the tubes 157.

15 Asphalt is placed within the container 157 and when a current is passed through the plate 150 through the wires 170 and 171, this plate will be heated and the asphalt will pass through the tubes 157^a. The hot gases issuing from the pipes 154 pass through the chamber 153 and will maintain the proper heat on said tubes to cause a continuous flow of the asphalt through said tubes.

20 25 30 35 It will be noted that the electric resistance members 160 are located at one side of the tubes 157 at their outer ends so that these portions of the tubes will have a temperature sufficient to aid in maintaining the flow of the asphalt through the outer ends of the tubes and will also facilitate in the cutting of the asphalt by the knives 165. It will be noted that the knives will be moved in the direction indicated by the arrow in Fig. 20 and have the greatest amount of heat applied to that portion of the tube which is farthest away from the knives or that point on the tubes where the knives complete the final shearing of the asphalt projecting from the tubes.

40 45 50 In Fig. 21 an electrical stove in the form of a coil 172 is provided to replace the heating means afforded by the pipe 154 of the construction shown in Fig. 20. In this case a wire 173 is connected with one terminal of a circuit and to the coil 172 so that the current passing through the coil will heat the resistance material in the coils and likewise heat the pipes 157^a. The other terminal of the circuit is represented by the wire 174. The other elements of this device will not be described since the same reference numerals applied to this figure represent similar elements employed in Fig. 20.

55 60 65 In Fig. 22 is shown diagrammatically a system in which a hot plate or screen 180 is electrically heated by a current passing through wires 181 and 182. This screen is mounted within a container 183. Gas burners 184 are directed against the lower portion of the container 183 which is below the electric resistance screen 180 for maintaining the lower portion of the container at the proper temperature in order to prevent too rapid congealing of the asphalt.

70 75 80 A plurality of pipes 185 have flattened nozzles 186 located adjacent the lower open end of the container 183 and are adapted to discharge fine streams of water across the lower end of the container in order to break the melted asphalt up into fine particles after it passes below the lower end of the container.

85 90 95 A tank 187 is located to one side of the container 183 and below the same to receive the fine particles of asphalt and the water which is forced towards the open upper end of said tank. This tank is maintained at a predetermined height with water in which has been stirred fine particles of mineral dust or clay so that the bath in the tank 187 will not only contain the fine particles

5 of asphalt but will contain the water and the fine mineral particles which may be held in suspension in the water. A screen 188 divides the tank 187 into two portions and retains the fine particles of asphalt within a greater portion of the tank. The screen prevents the asphalt from entering the smaller chamber 189 and the asphalt may be removed from time to time from the tank 187.

10 A pipe 190 is connected with the bottom of the chamber 189 of the tank 187 and with the pipe 185. A pump 191 is in circuit with the pipe 190 and forces the water from the chamber 189 to the nozzles 186. This pump is driven in any approved manner and at a speed which is commensurate with the work required. The muddy water is thus pumped from the tank 187 continuously, sprayed through the nozzle 186 across the lower end of the container 183, thereby breaking the asphalt up into small particles while coating the asphaltic mineral matter in order to maintain the particles of asphalt in a state of division.

A valve 193 is provided in the pipe 190 to cut off the water in the nozzle 186.

25 A pipe 194 is connected with the pipes 185 so that when a valve 195 is open air from a suitable source under pressure may be forced through the nozzle 186 across the lower end of the container 183, thus breaking the asphalt into fine particles.

30 It will be appreciated by this construction that either air or the muddy water may be employed or a combination of both. The mineral matter is supplied to the tank 187 from time to time in order to replenish the supply since the fine particles of asphalt are coated with said mineral dust as it comes in contact with the water carrying

35

as it comes in contact with the water carrying such dust.

they may be readily transported and that they
40 will not coalesce during transportation.

I claim:

1. A device for forming lengths of asphalt comprising a screen formed of a plurality of strips of resistance material, a plurality of strips of resistance material disposed transversely of the first-mentioned strips and forming with the first-mentioned strips restricted passages, a circuit including the strips for causing heating of the screen and melting of the asphalt placed on said screen to form strings of asphalt, the transverse strips being removable from the first-mentioned strips to provide elongated passages so that when asphalt is melted on the screen sheets of asphalt will be formed.

55 2. A device for dividing asphalt into fine particles comprising a container to receive asphalt, a screen in the container, means for heating the screen to cause the asphalt in the container to pass through said screen in the form of strings, 60 means projecting a stream of liquid across the protruding strings of asphalt for breaking the asphalt into fine particles, a tank partially filled with a liquid to receive the particles, the liquid aiding in maintaining the particles in a state 65 of division, and means for supplying the liquid from the tank to the projecting means.

3. A device for dividing asphalt into fine particles comprising a container to receive asphalt, a screen in the container, means for heating the screen to cause the asphalt in the container to pass through said screen in the form of strings, a nozzle located adjacent the lower end of the container, a tank partially filled with water containing finely divided mineral matter, a pipe connecting the tank with the nozzle, a pump inter-

polated in the pipe for forcing the water from the tank to the nozzle so that a stream of water will be forced across the strings of asphalt for breaking the asphalt into fine particles while coating the asphalt with the fine mineral which will act as a division agent. 5

4. A device for dividing asphalt into fine particles comprising a container to receive asphalt, a screen in the container, means for heating the screen to cause the asphalt in the container to pass through said screen in the form of strings, a nozzle located adjacent the lower end of the container, a tank partially filled with water containing finely divided mineral matter, a pipe connecting the tank with the nozzle, a pump interpolated in the pipe for forcing the water into the tank to the nozzle so that a stream of water will be forced across the strings of asphalt for breaking the asphalt into fine particles while coating the asphalt with the fine mineral which will act as a division agent, the tank being located adjacent the container when said tank will receive the coated particles of asphalt, the particles being further coated by the mineral matter in the water in said tank. 20

5. A device for dividing asphalt into fine particles comprising a container to receive asphalt, a screen in the container, means for heating the screen to cause the asphalt in the container to pass through said screen in the form of strings, means for projecting a stream of water containing fine mineral matter across the strings of asphalt for breaking said asphalt into small particles while coating said asphalt with mineral matter. 30 35

6. A device for dividing asphalt into fine particles comprising a container to receive asphalt, a screen in the container, means for heating the screen to cause the asphalt in the container to pass through said screen in the form of strings, 40 means for projecting a stream of water containing fine mineral matter across the strings of asphalt for breaking said asphalt into small particles while coating said asphalt with mineral matter, and means for collecting the particles of 45 asphalt in a bath of water containing finely divided mineral matter to cause further coating of said particles.

7. A device for melting and dividing asphalt comprising a casing forming a heating chamber and adapted to support asphalt thereon, tubular members extending through the chamber, means for heating the chamber and a heating means embracing the tubes between the inner and outer ends of said tubes so that the asphalt will be melted and pass through the tubes to form strings of the asphalt. 55

8. A device for melting and dividing asphalt comprising a casing forming a heating chamber and adapted to support asphalt thereon, tubular members extending through the chamber, means for heating the chamber and a heating means embracing the tubes between the inner and outer ends of said tubes so that the asphalt will be melted and pass through the tubes to form strings of the asphalt, and means adjacent the outer ends of the tubes for dividing the asphalt as it emerges from the tubes into small particles. 65

9. A device for melting and dividing asphalt comprising a casing forming a heating chamber and adapted to support asphalt thereon, tubular members extending through the chamber, means for heating the chamber and a heating means embracing the tubes between the inner and outer ends of said tubes so that the asphalt will be 75

melted and pass through the tubes to form strings of the asphalt, and knives for cutting off the asphalt into small particles as the asphalt emerges from the tubes.

- 5 10. A device for melting and dividing asphalt comprising a casing forming a heating chamber and adapted to support asphalt thereon, tubular members extending through the chamber, means for heating the chamber and a heating means 10 embracing the tubes between the inner and outer ends of said tubes so that the asphalt will be melted and pass through the tubes to form strings of the asphalt, knives for cutting off the asphalt into small particles as the asphalt emerges from 15 the tubes, and means for heating the knives.
11. A device for melting and dividing asphalt comprising a casing forming a heating chamber and adapted to support asphalt thereon, tubular members extending through the chamber, means 20 for heating the chamber and a heating means embracing the tubes between the inner and outer ends of said tubes so that the asphalt will be melted and pass through the tubes to form strings of the asphalt, knives for cutting off the asphalt 25 into small particles as the asphalt emerges from the tubes, and means for additionally heating the outer ends of the tubes.

12. A device for dividing asphalt into fine particles comprising a container to receive asphalt, a screen in the container, means for heating the screen to cause the asphalt in the container to pass through said screen, a tank partially filled 5 with a liquid containing finely divided mineral matter located adjacent the bottom of the container, means connected with the tank for projecting a stream of liquid from the tank across the protruding asphalt for breaking the asphalt 10 into fine particles, the tank receiving the particles with the liquid aiding in maintaining the particles in a state of division, the mineral matter coating the fine particles of asphalt.

13. A device for dividing asphalt into particles 15 or pellets comprising a screen, means for causing asphalt to be extruded through the screen, means for projecting a stream of liquid across the path of the extruding asphalt for cutting off the asphalt into particles, a tank containing a liquid to 20 receive the particles, and means connected between the projecting means and the tank for withdrawing liquid from the tank and forcing said liquid through the projecting means.
